UNITED STATES PATENT OFFICE.

WILLIAM W. SWENGEL, OF BLOOMSBURG, PENNSYLVANIA.

ROTARY DRIER.

1,240,386.

Specification of Letters Patent. Patented Sept. 18, 1917.

Application filed October 12, 1916. Serial No. 125,252.

To all whom it may concern:

Be it known that I, WILLIAM W. SWENGEL, a citizen of the United States, residing at Bloomsburg, in the county of Columbia 5 and State of Pennsylvania, have invented certain new and useful Improvements in Rotary Driers; and I do declare the following to be a full, clear, and exact description of the invention, such as will enable others 10 skilled in the art to which it appertains to make and use the same.

This invention is an improved drier having for its object to provide a simple, light, and compact machine which regardless of 15 these advantages, will be durable and will attain greater efficiency than heavier and more cumbersome machines now in use.

With the foregoing general object in view, the invention resides in certain novel features of construction and in unique combinations of parts to be hereinafter fully described and claimed, the descriptive matter being supplemented by the accompanying drawings which constitute a part of this application, and in which:

Figure 1 is a vertical longitudinal section of one form of the machine;

Fig. 2 is a transverse section thereof on the plane indicated by the line 2—2 of 30 Fig. 1;

Fig. 3 is a similar view on the plane indicated by the line 3—3 of Fig. 1;

Fig. 4 is a side elevation of a slightly different type of the improved drier;

Fig. 5 is a vertical section thereof on the plane of the line 5—5 of Fig. 4;

Fig. 6 is a similar view on the plane indicated by the line 6—6 of Fig. 4; and

Fig. 7 is a detail section showing the manner in which the material may be dried and screened at the same time.

In the drawings, the numerals 1 designate a pair of suitably constructed upright end frames between which a housing 2 is erected, said housing being of metal or masonry as occasion may demand. A plurality of vertically spaced drying drums 3 are disposed longitudinally within the housing 2, said drums having shafts 4 extending longitudinally therethrough and connected therewith by spiders 5, both ends of said shafts being rotatably mounted in suitable vertically adjustably rockably mounted bearings 6. Transverse driving shafts 9 are mounted rotatably in vertically adjustable bearings 10 secured to cross bars 11 of the frame 1. The bearings 10 may be adjusted

vertically in any preferred manner, but for illustrative purposes I have shown a plurality of washer plates 12 interposed between 60 said bearings and the bars 11. When the bearings are to be elevated, additional washer plates will be inserted, but when it is necessary to lower said bearings, certain of the previously applied plates will be removed.

The shafts 9 have pinions 13 keyed thereon, said pinions meshing with gears 14 which are secured to the shafts 4, whereby driving of said shafts 9 will rotate the several drums.

Any one of the shafts 9 may be driven and power transferred therefrom to the other shafts through the instrumentality of belts 15 and pulleys 16, the intermediate shaft 9 75 being shown in the present embodiment of the invention as having thereon a pulley 17 whereby it may be rotated. A feeder, a fan, and a conveyer are also driven from the intermediate shaft 9 as will be hereinafter described.

A furnace 18 supplies heat to the lower end of the casing 2 through a suitable heat inlet opening 19, this heat being directed around practically the entire circumference 85 of each drum 3 by a system of baffle plates 20 disposed in staggered relation and extending from the sides of the casing 2 into close proximity with the aforesaid drums. The top of the casing 2 has formed therein a 90 plurality of heat outlets 21 which discharge into a heat outlet conduit 22 which extends longitudinally above said top. A second heat conduit 23 is disposed vertically at one end of the housing 2 and one end of drums 3 95 extend into said conduit as shown clearly in Figs. 1 and 3. The other ends of said drums, however, project into an upright stack 24.

A rotary fan 25 is mounted in one end of the conduit 22 and is driven by a belt, 25' 100 from the intermediate shaft 9 above described, said fan being adapted to draw hot air from the casing 2 through the openings 21 and conduit 22, and to discharge this air into the stack 24 through the several drums 105 3. For permitting the fan 25 to operate in this manner, it is provided with an outlet pipe 26 disposed in conduit 23 and having a plurality of branches 27 which extend into the drums. By this arrangement of parts 110 it will be obvious that the heat within the casing 2 around the drums 3 will serve as drying means for the material passing through said drums and that the blasts of

hot air from the branches 27 will greatly increase the drying capacity of the machine.

- For supplying the machine with the material to be dried, hopper 28 having a discharge chute 29 is provided, said chute delivering into the upper end of the uppermost drum 3. Any suitable type of feeder 30 will be disposed in the hopper 28 and may well be driven by a belt 31 from the intermediate 10 shaft 9. As the material works its way through the upper drum and is discharged from the lower end thereof, it is directed into the upper end of the intermediate drum by an inclined chute 32 disposed in the conduit 23, and from the lower end of said intermediate drum, the material will be guided into the upper end of the lower drum by an additional chute 33 which, like the chute 29, extends across the stack 24. The lower end 15 of the last named drum delivers into a suitable conveyer 34 by means of which the dried material is taken from the machine, said conveyer being driven by a belt 34' from the driving shaft 9.
- 20 In Figs. 4, 5, and 6, the construction and arrangement of most parts is substantially the same, and the reference numerals above employed are therefore applied also to these figures. The main difference is that the heat 25 outlet conduit 22' is located at the bottom of the housing 2 while the furnace 18' delivers into the upper end of said housing rather than into the lower end thereof as above described. This necessitates placing the fan 25' at the lower end of the conduit 23' as shown. The operation and advantages of this form of the machine are the same as that above described and further explanation is therefore deemed unnecessary.
- 30 Fig. 7 discloses a drum 3^a which may be employed at the bottom of either form of the machine, said drum having therein a screen 3^b whereby sand or the like being dried by the machine may be screened at the 35 same time.
- 40 When setting up the improved machine in any of its forms, the inclination of the drums 3 will be initially adjusted according to the character of the work to be done, but after 45 these adjustments have been made, said drums may remain unmolested unless it is desired to employ the machine for a different class of work. The proper adjustments having been made, a fire will be built in the 50 furnace 18 and the machine will then be set into operation, the damp material being supplied thereto from the hopper 30 and taken 55 therefrom by the conveyer 34, this material passing successively through the upper, intermediate, and lower drums. It is to be 60 observed that while this takes place no one of the drums will receive the moisture from any of the others, since all of said moisture

will be taken from the several drums by the blasts of air forced therethrough from the 65 branches 27. This is a highly important feature of the invention, although I of course understand that I am not the originator of a machine in which blasts of air are directed through rotating drums. In so far as I am 70 advised, however, the general organization of parts shown and described are novel and it is this arrangement and not any particular part thereof upon which I seek Letters Patent.

75 From the foregoing, taken in connection with the accompanying drawings, the construction, manner of operation and advantages of the improved machine will be readily understood without requiring a more extended explanation, but in conclusion I will state that although a number of specific details have been shown and described for accomplishing probably the best results numerous changes may be made within the 80 scope of the invention as claimed.

I claim:

1. In a rotary drier, the combination of a plurality of vertically spaced rotary drums through which the material to be dried is 90 adapted to travel, a housing surrounding said drums and having a hot air inlet and a hot air outlet, the one being at the top of the housing and the other at the bottom thereof, a vertically extending conduit 95 with which the drums communicate at one end, a stack with which the other ends of said drums communicate, a fan for drawing hot air from the outlet of the housing, and means leading from the outlet of said fan 100 for directing the hot air discharged therefrom through the drums into the stack.

2. In a rotary drier, the combination of a plurality of vertically spaced rotary drums through which the material to be dried is 105 adapted to travel, a housing surrounding said drums and having a hot air inlet and a longitudinally extending heat outlet conduit, the one being disposed at the top of the housing and the other at the bottom thereof, 110 a vertical conduit with which the drums communicate at one end, a stack with which the other ends of said drums communicate, a fan in the aforesaid heat outlet conduit for drawing hot air therefrom, and an outlet pipe from said fan located in the aforesaid vertical conduit and having branches 115 for directing the hot air discharge from the fan through the drums into the stack.

120 In testimony whereof I have hereunto set my hand in the presence of two subscribing witnesses.

WILLIAM W. SWENGEL.
